United States Patent Office

Des. 221,577
Patented Aug. 24, 1971

221,577

CAKEPAN OR THE LIKE

Florene Joy Ramboldt, 12026 Dresden Place,
Los Angeles, Calif. 91344

Filed July 8, 1970, Ser. No. 23,868

Term of patent 14 years

Int. Cl. D7—02

U.S. Cl. D44—1

FIG. 1 is a top perspective view of a cake pan embodying my new design;

FIG. 2 is a top plan view thereof;

FIG. 3 is a bottom view thereof;

FIG. 4 is an end view of one end thereof;

FIG. 5 is a side elevational view thereof; and

FIG. 6 is a cross-sectional view thereof taken in the direction 6—6.

I claim:

The ornamental design for a cakepan or the like, as shown.
